UNITED STATES PATENT OFFICE.

CHARLES H. SNIDER, OF MOUNT PLEASANT, MICHIGAN.

MOUNTING FOR SLIDE DOORS AND WINDOWS.

1,408,543.

Specification of Letters Patent. Patented Mar. 7, 1922.

Application filed November 12, 1920. Serial No. 423,643.

To all whom it may concern:

Be it known that I, CHARLES H. SNIDER, a citizen of the United States, residing at Mount Pleasant, in the county of Isabella 5 and State of Michigan, have invented certain new and useful Improvements in Mountings for Slide Doors and Windows, of which the following is a specification.

The present invention has a reference to 10 sliding door or window construction and aims to provide improved means of mounting sliding doors and windows in such a manner that they can be conveniently operated at all times, and without binding or 15 sticking in damp and rainy weather.

An additional object is to provide an improved mounting structure capable of general application and designed to admit of use in connection with the closed tops or 20 cabs of motor vehicles.

With the above and other objects in view, the invention may be said to reside generally in the details of construction, combination and arrangement of parts as will be herein- 25 after more fully pointed out and described, reference being had to the accompanying drawings, wherein:

Figure 1 is a side elevation, illustrating the application of the invention as viewed 30 from the outside of the structure to which it is applied;

Figure 2, a cross sectional view taken on the line 2—2 of Figure 1;

Figure 3, a side elevation, disclosing the 35 invention as viewed from the inside, and

Figures 4 and 5, detail, fragmentary views, illustrating respectively, the top and bottom slide members.

The invention is intended to be used for 40 any sliding window or door, where ease of operation is desirable, and is therefore not to be considered as limited to the particular application herein illustrated.

In the present embodiment of the invention, the supporting structure 1 may be 45 either of wood, as in building construction, or leather, as in the case of an auto vehicle side curtain. In either case, the window space 2, is provided, upon the inside, with 50 bordering strips 3 and 4, extending longitudinally of the top and bottom edges of the window space, and forming respectively, the supports for the upper and lower track rails. These supporting strips are prefer- 55 ably of a width equal to the width of the sliding sashes, and may be fastened to the

supporting structure 1, in any suitable manner.

The top track rail 5, is formed of a long metallic strip, projecting beyond both sides 60 of the window space, and made approximately V-shaped or angular, throughout its length to engage the lower inside corner of the strip or frame 3. Depending from the underside of the rail 5 is a flange 6, which 65 constitutes the upper guide rail or track. The lower member is formed of a flat metallic strip, secured to the top edge of strip 4, and having its innermost longitudinal edge extended upwardly to provide a track rail 8, 70 similar to upper rail 6, but slightly offset, with respect to the latter, as shown to advantage in Figure 2 of the drawings.

Arranged for cooperation with the tracks are sash-carrying members 9 and 10, of similar construction so that a description of one 75 will suffice for both of them. The sash carriers are respectively disposed along the upper and lower edges of the sashes and each consists of a metallic strip, having a longitudinal portion extended angularly with respect to the flat or securing portion 11; the angularly disposed portion being folded upon itself to provide a channel or grooved member, as indicated at 12. 80

Each sash 13, has its upper and lower edge provided, in the one case with a recess 14, and in the other with a cut away corner 15, to receive the channel bearing portion 12 of the carrier members, it being noted that the latter are fastened to the sashes, with the channel portions disposed inwardly, and the slot portions providing tread plates or sliding surfaces, for their respective sashes. When so arranged, the track rails 6 and 8, fit into 95 the grooves or channels of the carrier portions 12 and 14, and serve to prevent any lateral movement of the sashes, although permitting them to be freely moved longitudinally in either direction. Each sash may be 100 separately provided with any suitable type of window, as indicated at 16, in order that a view of the outside may be obtained in rainy and inclement weather, when the window sashes are in closed position as illustrated in 105 Figure 1.

Being freely slidable to and fro between the upper and lower supporting rails, it is obvious that the window can be readily and conveniently opened by shifting the sashes to 110 either side of the window space where they are conveniently disposed out of sight from

the outside. By arranging the track members upon the inside of the sashes and adjacent the innermost edge of the window, they are thereby much more protected from the weather and provide an open contact between the slide units of the window construction, permitting relative expansion and eliminating the binding and stalling defects usually occasioned when the sashes expand within their frames in inclement weather, tending to stick firmly in place, and resisting any attempt to move them to a shut or open position.

The advantages of a metallic mounting comprising interfitting, slidably engaged members, as above described, are thought to be evident, from the above disclosure, and its adaptability to uses other than that related to automobile tops, fully understood.

Having thus described the invention, what I claim as new and desire to secure by Letters Patent is:—

In a device of the character described the combination with upper and lower sup-

porting strips, of a top rail formed of a metallic strip having a depending guide flange, a lower rail comprising a metallic strip having an upstanding guide flange extending parallel to said first flange, an upper sash carrier arranged to be held between said flanges, said upper carrier including a securing portion from which extends a downwardly extending channeled portion arranged to be held in a recess of a guide, said channel portion adapted to hold said downwardly extending guide flange, and a lower sash carrier comprising an upstanding channel portion extending from the securing portion, said channel portion arranged to be held in a cut away portion of the sash and adapted to receive said lower guide flange, all substantially arranged as set forth.

In testimony whereof I affix my signature in presence of two witnesses.

CHARLES H. SNIDER.
